DOOR HANDLE

Ray C. Sandin, Winnetka, and Jon F. Morgan, Glen Ellyn, Ill., assignors to General Electric Company, a corporation of New York

Filed May 3, 1963, Ser. No. 74,732

Term of patent 7 years

(Cl. D81—25)

FIG. 1 is a top plan view of a door handle showing our new design;

FIG. 2 is a side elevational view thereof;

FIGS. 3 and 4 are, respectively, enlarged fragmentary, top plan and side elevational views thereof;

FIG. 5 is an end elevational view thereof, it being understood that each end is identical;

FIG. 6 is a vertical sectional view, looking in the direction of the arrows 6—6 of FIG. 4;

FIG. 7 is a vertical sectional view, looking in the direction of the arrows 7—7 of FIG. 4; and

FIG. 8 is a vertical sectional view, looking in the direction of the arrows 8—8 of FIG. 4.

We claim:
The ornamental design for a door handle, substantially as shown and described.
